UNITED STATES PATENT OFFICE.

HAROLD D. PENNEY, OF PELHAM, NEW YORK, ASSIGNOR TO DIAMOND EXPANSION BOLT COMPANY, A CORPORATION OF NEW YORK.

SOUND AMPLIFIER.

Application filed October 16, 1923. Serial No. 668,840.

The present invention relates to an improvement in a sound resonating and amplifying device; and in its application to the useful arts, it may be applied to, and transmit sound from, various types of tonal or sound initiating devices, such as phonographs and receivers of telephones and is found useful in amplifying incoming signals in radio receiving apparatus. In combination with a radio-phone, having suitable connection with a radio amplifying set, it may be useful as a loud speaker. I do not desire however, to be held to any of the above noted uses or radio broadcast reception or amplification alone.

In the drawings herein,

Fig. 1 is a front elevation of one form of the invention;

Fig. 2 is a sectional view taken on a vertical diameter of Fig. 1;

Fig. 3 is a sectional view showing a standard megaphone horn;

Fig. 4 is a diagrammatic view showing a form of attachment for phonographic sound transmission and amplification;

Fig. 5 is a sectional view of another form of the invention;

Fig. 6 is a front view of another form of the invention; and

Fig. 7 is a perspective view of still another form of the invention.

In Fig. 1, my device is shown in the form that is preferred from the standpoint of quality of tone, and here comprises two preferably wooden associated members 1 and 2, mounted upon a suitable base 3, here shown as a separate piece, an annular chamber, when viewed from the front, being formed between the members 1 and 2.

The member 1 has a concave reflecting surface or face 4, which when viewed in section as in Fig. 2, is in form the longitudinal segment of an oval interrupted at its middle by the sound admitting orifice or aperture 5, and the member 2 has a convex reflecting surface of arc of circle form with converging curved portions at the ends of the arc, the member 2 facing the aperture 5 and extending a distance on either side thereof, the chamber or passage 6 for passage of sound through the device being formed between the members 1 and 2 and having outlets for sound at its ends, the member 1 being the sound reflecting ele-

ment or resonator and the member 2 being the sound deflecting or modulating element.

As later explained the member 2 may be adjustably movable for constricting the sound in said chamber or passage adjacent to the aperture 5 for modulating the sound, and it will be noted that when the member 2 is so moved, although the passage 6 will be constricted adjacent to the aperture 5 and the capacity of the passage 6 for passage of sound varied or altered at this point, the contour for passage of sound of this chamber or passage will be substantially unaltered both at said inlet and outlets, the modulation by the member 2 thus causing no distortion or change of direction of the sound in its passage through the chamber or passage 6, the member 2 thus efficiently and perfectly performing its function as a modulator.

While the device of Figs. 1 and 2 is preferably of wood, the invention may be in the form of a pair of spun metal shells as indicated in Fig. 5, and it will be noted, in both forms, that the outer major reflector element 1 is, from front to rear, comparatively narrow and has a contoured inner tone reflecting surface 4 which terminates, preferably as an orifice or aperture 5 at the rear or back portion B of the element 1, Fig. 2. In the present showing, this back aperture is arranged to receive and to maintain in operative relation thereto, a loud speaker phone, generally denoted by P, and this phone may be of the well known Baldwin Westinghouse phonograph type or equivalent, usually utilized for adaptation to phonograph reception and amplification of radio signals.

Affixed near the center of the contoured inner surface 4 is a central or minor tone deflector element 2, which is affixed in the basin-like tone depression of the major element 1, and it will be seen, that the chamber formed by the contour of the associated elements 1 and 2 is somewhat in the nature of a double megaphonic amplifying tone chamber, such as is shown at C, Fig. 3, which is an approximate outline of the well known amplifying horn such as is customarily used in loud speakers of this type.

It will also be noted, that the upper or lower half of either section of the tone chamber 6, Fig. 2, also partakes of this

megaphonic horn contour as indicated at C, Fig. 3, and that therefore this chamber 6, instead of being a single tubular-like chamber as is customary in horns of this 5 type, is, when viewed from the front, in an annular form such as is indicated by Fig. 1.

It will be further noted that in order to afford this contour that the major reflector element 1 and the minor deflector element 10 2 are so conformed at their opposed adjacent surfaces that the outer major element 1 forms an equivalent to the back wall W of the megaphone element M shown in Fig. 3, and that the minor element 2 forms an equivalent 15 of the inner wall I of the megaphonic element 1 shown in Fig. 3, so that instead of my device being a large tubular cone as indicated in Fig. 3, my tone amplifying or diffusing device is so constructed that 20 the constricted section at the orifice 5, Fig. 2, is equivalent to the constricted tubular portion O, Fig. 3, and that the bell-like amplifying chamber C, Fig. 3, is substantially like the upper or lower section of chamber 25 6, Fig. 2.

In other words, I have created a modified amplifying tone deflector which permits of the use of standard phones of the radio or telephonic type therewith; and it may also 30 be utilized in connection with phonographs in which the tone arm T, Fig. 4, is operatively connected therewith in which D represents the diaphragm box of the ordinary well known phonograph connection, the tone 35 arm terminating in the aperture 5, which is here made somewhat larger than in the device of Fig. 2.

In Fig. 5, there is disclosed a modified construction which, while not so desirable 40 for certain reasons to be hereinafter set forth, yet on the score of economy this form of construction may be easily encompassed at a minimum of cost.

In Fig. 5 the reference numerals are the 45 same as for the equivalent structural details shown in Fig. 2, and represent corresponding portions of the structure, but instead of the major element 1 being made of wood, it is lathe-turned, or molded, in the usual manner, in the present instance being made of 50 stamped or pressed sheet metal, and the element 2 is likewise made of stamped or pressed metal construction, so that, in effect, the tone channel portion 6 is of substantially 55 the same character and general contour as shown in Fig. 2.

However, it is to be noted that I have found in actual practice that the all wood form as shown in Fig. 2, gives somewhat better 60 tone qualities than the all metal form indicated in Fig. 5, due to the more natural resonance characteristic of wood itself. On the other hand the difference in the manufacturing costs between the all metal form and the all wooden form as shown, would

warrant in some instances, the making of the flat megaphonic device herein disclosed, of sheet metal.

In the present construction, I have found that the volume of sound emitting from this 70 device is about equivalent in volume and quality to the ordinary well known type of megaphonic horn of equal volumetric content, and, in addition thereto, the present type of device, being comparatively narrow 75 in sectional area as indicated at Fig. 2, may be made in various ornamental forms in either metal or wood, and takes up a much smaller space than heretofore. In addition it is not at all unsightly and in its outer or 80 exterior conformation it may be made to suit various periods of wood or furniture construction, as to the ornamentation thereof, and at the same time becomes a very practical and ornamental device. 85

It will furthermore be noted that by making the device narrow and creating therein a tone chamber having a constricted area at the phone receiving point, and swelling the chamber to a larger dimension at the point 90 of emission outside of the plane of the front face thereof, that I have created a flat megaphone of narrow cross sectional area, which answers every purpose to which the well known type of megaphone has been heretofore adapted, making it much easier to carry when such is required and affording a more economical method of manufacturing and doing away with the tubby resonance encountered in the usual tubular type of construction such as is shown in Fig. 3. 95

In effect, when the two component elements 1 and 2, which are affixed to each other in operative relation, by means of screws or rivets 7, the structure, as such, 100 becomes unitary and presents a single structure having when viewed from the front an annular tone-amplifying chamber within the comparatively narrow section of the body thereof. The annular tone chamber thus developed between the two disk-like elements 1 and 2 has all the characteristics of a megaphone amplifying horn and lends itself to a better reproduction of tone, well modulated and pleasing to the ear. 110

The screws 7, Fig. 2, may be so arranged 115 that they may be adjusted, thereby moving and holding in adjusted position the deflector or modulator element 2, relative to the major reflector 1, whereby the narrow portion of the tone chamber 6, may be constricted or increased at will, if desired. This is shown by the dotted lines z, Fig. 2, which indicate constriction of the tone chamber 6, over the normal, and which constriction 120 causes modification of the issuing tone.

Throughout the herein description, I have described my device as having an "annular" tone passage therein, when viewed from the front, and formed by a reflector element and 130

a deflector element. The structural limitation thereby referred to is a concession to the economical manufacture of this type of preferred form, by turning the same in a lathe, which, as is well known, is a rapid and economical method of manufacture.

However, it is not at all necessary as I have discovered, that the device be limited to an annular tone passage, in the sense of one having a constant radius, since the said passage may be rectangular in its visual configuration such as is instanced in Fig. 6, wherein the front view of the chamber 6 is substantially rectangular, the sectional view of this modification being exactly the same as that shown in Fig. 2, all other ordinals thereon representing equivalents as described for Fig. 2.

It is also possible in some forms of my device to mold the same, forming by this process of manufacture, a unitary, comparatively wide face of relatively narrow cross section, which cross section is traversed by the narrow gradually increasing tone passage as outlined in the foregoing description.

The form of invention shown in Fig. 7 is very similar to that of Figs. 1 and 2, except the resonating element has a somewhat pointed shape when viewed from the front, and the modulating element carries on its front an ornament 8. Many other forms of the invention will readily suggest themselves.

I claim as my invention:

1. In combination, a wide major reflector element having its front face concaved to form a wide shallow chamber having a diameter several times greater than its depth and having a short central aperture therein; said reflector element being adapted to receive a telephone mounted adjacent to the back of said reflector element with its diaphragm close to and emitting sound through said aperture directly into said chamber to form a zone of intense sound waves within said chamber close to said aperture; and a minor deflector element having a convexed rear face coaxially disposed in said zone a short distance in front of said aperture and to extend on all sides thereof and cooperating with the concaved face to diverge the intense waves and form a sound reflecting and amplifying chamber having a gradual outward and forward flare of gradually increasing angle of flare to the periphery.

2. In combination, a wide major reflector element having its front face concaved to form a wide shallow chamber having a diameter several times greater than its depth and having therein a central aperture wider than it is long; said reflector element being adapted to receive a telephone mounted on the back of said reflector element with its diaphragm spaced from the aperture a distance less than the diameter of the aperture;

and a minor deflector element having a convexed rear face coaxially disposed a short distance in front of said aperture and cooperating with the concaved face to form a sound reflecting and amplifying chamber having a gradual outward and forward flare of gradually increasing angle of flare to the periphery.

3. A sound amplifier comprising a wide major reflector element having its front face concaved to form a wide shallow chamber having a diameter several times greater than its depth and having a short central aperture therein; said reflector element being adapted to receive a telephone mounted adjacent to the back of said reflector element with its diaphragm close to and emitting sound into said aperture; and a minor deflector element having a convexed rear face coaxially disposed a short distance in front of said aperture and cooperating with the concaved face to form a sound reflecting and amplifying chamber having a gradual outward and forward flare of gradually increasing angle of flare to the periphery; diametrically opposite parts of said amplifying chamber being disposed substantially at an obtuse angle to each other, the space at the axis of the amplifier forward thereof being comparatively free of sound waves.

4. In combination, a wide major reflector element having its front face concaved to form a wide shallow chamber having a diameter several times greater than its depth and having a central aperture therein shorter than its diameter; said reflector element being adapted to receive a telephone mounted adjacent to the back of said reflector element with its diaphragm close to and emitting sound into said aperture to form a zone of intense sound vibration within said chamber close to said aperture; and a single minor deflector element having an imperforate uninterrupted convexed rear face coaxially disposed in said zone a short distance directly in front of said aperture and cooperating with the concaved face to form a sound reflecting and amplifying chamber having a gradual outward and forward flare of gradually increasing angle of flare to the periphery.

5. In combination, a wide major reflector element having its front face concaved to form a wide shallow chamber having a diameter several times greater than its depth and having a short central aperture therein; said reflector element being adapted to receive a telephone mounted adjacent to the back of said reflector element concentric with said aperture with its diaphragm close to and emitting sound into said aperture; a minor deflector element having a convexed rear face coaxially disposed a short distance in front of said aperture and cooperating with the concaved

- face to form a sound reflecting and amplifying chamber; and adjusting means adjustably supporting said minor deflector for moving it toward or from the aperture; 5 said amplifying chamber having a gradual outward and forward flare of gradually increasing angle of flare to the periphery for any position of adjustment of the minor deflector element.
- 10 6. In combination, a wide major reflector element having its front face concaved to form a wide shallow chamber having a diameter several times greater than its depth and having a central aperture therein; 15 said reflector element being adapted to receive a telephone mounted adjacent to the back of said reflector element with its diaphragm close to and emitting sound into said aperture; a minor deflector element having a convexed rear face coaxially disposed a short distance in front of said aperture and cooperating with the concaved face to form a sound reflecting and amplifying chamber having a gradual outward and 20 forward flare of gradually increasing angle of flare to the periphery; and adjusting means entirely exterior to said aperture adjustably supporting said minor deflector for moving it toward or from the aperture.
- 25 7. In combination, a wide major reflector element having its front face concaved to form a wide shallow chamber having a diameter several times greater than its depth and having a central aperture; said reflector element being adapted to receive a telephone mounted and supported to the back of said reflector element with its diaphragm close to said aperture; a minor deflector element having a convexed rear face carried by the 30 major element a short distance in front of said aperture and cooperating with the concaved face thereby to form a sound reflecting and amplifying chamber having a gradual outward and forward flare of gradually 35 increasing angle of flare to the periphery; and a base fixed to the lower part of the periphery of the major element and supporting the latter and thereby the telephone and the inner element.
- 40 8. A sound amplifier comprising a wide major reflector having its front face concaved to form a wide shallow chamber having a diameter several times greater than 45 its depth and having a central aperture 55 therein; said reflector element being adapted to receive a telephone mounted on the back of said reflector element with its diaphragm close to the aperture; and a minor deflector element having a convexed rear face coaxially disposed a short distance in front of said aperture and cooperating with the concaved face to form a sound reflecting and amplifying chamber having a gradual outward and forward flare of gradually increasing angle of flare to the periphery; 60 the front to rear depth of said amplifier as a whole including the telephone being less than half the diameter of the major deflector.
- 65 9. In combination, a wide major reflector element having its front face concaved to form a wide shallow chamber having a central aperture therein and having a diameter several times greater than its depth; a minor deflector element having a convexed rear 70 face coaxially disposed a short distance in front of said aperture and cooperating with the concaved face to form a sound reflecting chamber having a gradual outward and forward flare of gradually increasing angle of flare toward the periphery; and a base fixed to the lower part of the periphery of the major reflector element for supporting the latter.
- 75 10. In combination, a wide major reflector element consisting of a block of wood having parallel front and rear faces having a height more than three times its thickness; the front face of said element being concaved to form a wide shallow chamber 80 having a central aperture therein and having a diameter several times greater than its depth and nearly equal to the width of the block; and a minor deflector element having a convexed rear face coaxially disposed a short distance in front of said aperture and cooperating with the concaved face to form a sound reflecting chamber having a gradual outward and forward flare of 85 gradually increasing angle of flare toward 90 the periphery.
- 95 Signed at 253 B'way, New York city, in the county of New York and State of New York, this 15th day of October A. D. 1923.

HAROLD D. PENNEY.
